(57) **CLAIM**

The ornamental design for a propane tank holder, as shown and described.

DESCRIPTION

FIG. 1 is a top perspective view of our new design for a propane tank holder;

FIG. 2 is a top plan view thereof;

FIG. 3 is a side elevation view thereof;

FIG. 4 is a bottom perspective view thereof;

FIG. 5 is a bottom plan view thereof;

FIG. 6 is a cross-sectional view thereof, taken along line 6-6 of FIG. 5; and,

FIG. 7 is a cross-sectional view thereof; taken along line 7-7 of FIG. 5.

The broken line showing of a propane tank in FIG. 1 is included for purposes of illustrating environment and forms no part of the claimed design.
